UNITED STATES PATENT OFFICE.

FRANKLIN P. JACKSON AND JOHN W. SKINNER, OF QUINCY, ILLINOIS; SAID SKINNER ASSIGNOR TO LAWRENCE E. EMMONS, OF SAME PLACE.

TOBACCO-PRESS.

SPECIFICATION forming part of Letters Patent No. 302,337, dated July 22, 1884.

Application filed May 29, 1884. (No model.)

To all whom it may concern:

Be it known that we, FRANKLIN P. JACKSON and JOHN W. SKINNER, both of Quincy, in the county of Adams and State of Illinois, have invented certain new and useful Improvements in Tobacco-Presses; and we do hereby declare the following to be a full, clear, and exact description of the same, reference being had to the accompanying drawings, forming a part of this specification, and to the figures and letters of reference marked thereon.

Our present invention has reference to improvements in the construction of the press boxes or shapes used in forming and pressing plug and smoking tobacco; and it consists in the novel construction and combination of the several parts or members forming said shapes, whereby the pockets or receptacles for the tobacco may be adjusted and the parts rendered interchangeable, all as hereinafter more fully described, and pointed out in the claims.

In the accompanying drawings, Figure 1 is a view in perspective of our improved press box or shape with follower raised out of position. Fig. 2 is a plan view of the press-box. Fig. 3 illustrates a modification of our invention. Fig. 4 is a view of the end piece B.

Similar letters of reference in the several figures indicate the same parts.

The metal plate A, forming the bottom of the press box or form, is provided with a fixed end piece, B, and two vertical guiding-brackets, C. Both the end pieces B and brackets C are provided with elongated slots or openings b c, for the reception of pins or screws fastened to the ends of the movable side pieces D. The slots in the end piece B may, if desired, be closed at the end by plates b'. The inner or contiguous faces of the side pieces D are made parallel, and formed with vertical slots or grooves d, for the reception of the removable division-plates or partitions E, and the outer faces of the side pieces taper or incline toward the end piece B, and are provided with the guiding-strips d'. The press box or shape thus constructed is received within a frame formed upon or attached to the base-plate or press-table F. This frame is composed of the base-plate F, end piece F',

and side pieces F², the inner faces of the latter being inclined at the same angle as the outer faces of the side pieces D of the press-box, and also provided with longitudinal slots, forming ways for the strips d'.

In using our improved press box or shape it is placed in position upon the base-plate F and withdrawn from between the side pieces F², the division-plates or partitions E being removed. The workman then takes the material to be pressed, and, after separating or forming a mass of the proper size, weight, or quality, he pushes it into place against the end pieces B and inserts a division-plate in the first pair of slots. The same operation is repeated until each receptacle is in turn filled and the division-plates inserted. When the press-box proper is thus fully charged, it is pushed forward in between the side pieces F², and by reason of the inclined or wedge shape of these pieces the side pieces D are forced together, thus confining the partitions firmly in place, the grooves being of sufficient depth to permit the proper degree of movement. The upper plate, H, with its plungers I, of proper size and form to fit the several compartments contained in the press-box, is then brought down and the whole submitted to the action of the press.

As will be obvious, the press-box above described possesses numerous advantages both as regards its construction and manipulation. By employing side bars of different widths or with the vertical slots for the reception of the partition-plates at different distances apart, it may be readily adapted to receive and press longer or wider lumps or plugs. Moreover, by its use we are enabled to accurately and expeditiously form or produce lumps or plugs of exact weight and size with straight sides and square corners.

When desired, two or more press boxes or shapes may be adapted to the same base-plate or press-table, and to accomplish this it is only necessary to insert between the side pieces F² a double-inclined or wedge piece, F³, as shown in Fig. 3, the base or larger end of the wedge resting against the end piece F'.

Having thus described my invention, what

I claim as new, and desire to secure by Letters Patent, is—

1. In combination with the base-plate or press-table and its fixed inclined side pieces, the removable press-box consisting of the plate, the removable side pieces supported thereon, and the removable partitions, substantially as described.
2. In combination with the plate and its attached end piece and brackets, slotted as described, the movable side pieces united to the end piece and brackets by the pins or screws, and the removable partitions, as and for the purpose set forth.
3. In combination with the fixed side pieces

having inclined faces, the movable plate carrying the inclined and grooved side pieces, and removable partitions, substantially as described.

4. In combination with the fixed inclined side pieces, the removable wedge-piece, and the press-boxes, each composed of a plate, two removable side pieces, inclined and grooved as described, and the removable partitions, as and for the purpose set forth.

FRANKLIN P. JACKSON.
JOHN W. SKINNER.
